UNITED STATES PATENT OFFICE.

FRANZ TRINKS, OF BRUNSWICK, GERMANY.

CALCULATING-MACHINE.

1,072,324.

Specification of Letters Patent.

Patented Sept. 2, 1913.

Application filed January 30, 1912. Serial No. 674,241.

Be it known that I, FRANZ TRINKS, manufacturer, a subject of the Duchy of Brunswick, Empire of Germany, residing at 71 Kastanienallee, Brunswick, Germany, have invented certain new and useful Improvements in Calculating-Machines, of which the following is a specification.

My invention relates to improvements in calculating machines, and more particularly to calculating machines of that class, in which the values of the calculations are set on a plurality of setting disks by shifting the desired number of teeth into operative position, and transferred to numeral wheels by rotating the setting disks by means of a crank. To permit continuous multiplications of the form

$$a.m+b.n+c.o+,$$

etc., to be performed by means of machines of this class two sets of numeral wheels are arranged one beside the other on a common slide or carriage, and the said sets of numeral wheels coöperate with two sets of setting disks which are likewise arranged one beside the other.

One of the objects of the improvements is to arrange the setting disks and numeral wheels in such a way, that the machine can be used as well for performing the continuous calculations above referred to or, if desired, a single calculation of exceptionally high numbers.

With this object in view my invention consists in arranging the sets of numeral wheels without interruption one beside the other, and in such a way, that each set of numeral wheels can be used in combination with the adjacent setting mechanism, or, if desired, and where calculations of exceptionally high numbers must be performed, that both sets of numeral wheels can be used as a single one in combination with one of the sets of setting disks.

Furthermore my invention consists in so constructing the revolutions counting mechanism for counting the revolutions of the setting disks (or the crank), that the single tooth operating the revolutions counting mechanism remains in operative position relatively to the latter, even if by shifting the carriage, the set of numeral wheels located at the left hand side of the carriage

has been brought into coöperation with the set of setting disks located at the right hand side of the machine.

In order that my invention be more clearly understood an example embodying the same has been shown in the accompanying drawings, in which the same letters of reference have been used in all the views to indicate corresponding parts.

In said drawings—Figure 1, is a front view of a calculating machine of known construction in which my invention may be embodied, the casing of the machine being partly removed, Fig. 2, is a cross-section taken along the line 2—2 of Fig. 1.

Reference will now be had to the drawings.

A rotary shaft 63, mounted in a pair of side walls 61 and 62, is operatively connected with the machine crank 64 through spur gears 65 and 66, and it carries a plurality of setting disks 67 each of which is provided with nine radially shiftable teeth 68, engaged by a cam disk 69. In front of the said setting mechanisms 67, 68, 69, 69', numeral wheels 7 are loosely mounted on a shaft 9 disposed parallel to the shaft 63. 80 Each numeral wheel, the numerical characters of which are visible through a peep hole 72' in a cover 72, has a spur gear 73 which is in mesh with the teeth of a transmission wheel 13, loosely mounted on a 85 shaft 12. The said transmission wheels 13 are located in the plane of the radially shiftable teeth 68 of the setting disks 67.

Carrying means are provided between consecutive numeral wheels. In the example illustrated the counting wheels 7 are provided with hammer-shaped carrying levers 76, loosely mounted on a shaft 76 disposed parallel to the axis 9. The levers 76 extend with their free upper ends 76'' in 90 known manner in the path of pins 7' of the numeral wheels 7, whereby the levers 76 are rocked, when the numeral wheels pass from their "9" position into their "0" position, or vice versa. Thereby a cam face 190 76'' of the rocking lever 76 is thrown into the path of laterally shiftable teeth 67' of the coöoperating setting disk 67, adapted to coöperate, when shifted, with the transmission wheel 13 coöperating with the numeral wheel 7 of the next higher order.

Cam faces 67" rock the levers 76 into their normal positions shown in Fig. 2.

At the left of the registering mechanism 7 a second registering mechanism 78 is provided for counting the revolutions of the machine crank, which revolutions counting mechanism is actuated from the shaft 63 by means of a single tooth wheel 79 advancing a spur gear 80. Each of the numeral wheels 10 is connected with a gearing 81, and all the gear wheels 80 meshing with the gearings 81 are loosely mounted on a shaft 84 disposed parallel to the shaft 70 of the registering mechanism 78.

15 Both registering mechanisms 7 and 78 are provided with resetting mechanisms adapted to set the numeral wheels into their zero positions. At its outer end the shaft 9 carries a nut 11, and within each of the numeral wheels 7 it is provided with a radial pin 9' coöperating with an abutment 10 of the numeral wheels 7. Upon rotation of the shaft 9 by means of the nut 11 the shaft 9 is shifted laterally against the action of a spring 89 by means of a cam face 88, so that the pins 9' are shifted into the path of the abutments 10 whereby the wheels 7 are turned to their zero positions. Resetting mechanisms of the same construction are provided on the shaft 70 which carries a nut 90 at its outer end. Short sleeves 85 prevent the axial displacement of the wheels 7 and 78.

Referring now more particularly to the 35 construction forming my invention the registering mechanism which consists of the sets of numeral wheels 7 and the revolutions counting mechanism 78 are mounted on a common carriage or slide 1 which is 40 slideable in a direction parallel to the shaft 63, so that the setting disks 67 of the lower order (shown at the right in Fig. 1) can be brought into coöperation with the numeral wheels 7 of the higher order (shown 45 at the left in Fig. 1). Whereby in case of multiplications with high numbers the necessary number of revolutions of the crank is reduced.

The carriage 1 carries two sets of numeral 50 wheels 7² and 7³ which are located coaxially with the revolutions counting mechanism 78, and each of which coöperates with a setting mechanism 69² and 69³ respectively, and the sets of numeral wheels are arranged 55 without interruption one beside the other, the distance of the adjacent numeral wheels 7² and 7³ of the sets 7² and 7³ being the same as the distance of the other numeral wheels. Accordingly also the peep holes 60 72' of both sets of numeral wheels 7² and 7³ are arranged in uninterrupted succession, the distance of all the peep holes being the same, and the distance of the adjacent setting disks 69² and 69³ is a multiple of the 65 ordinary distance of the setting disks. The

division line between both numeral wheels may be indicated by any suitable mark, for example by means of an arrow y.

In my improved calculating machine the set of numeral wheels 7² can be used in co-operation with the set of setting disks 69² and the set of numeral wheels 7³ can be used in coöperation with the set of setting disks 69³, as is known in machines of this class. However, apart from this, if exceptionally large calculations must be performed, both sets of numeral wheels 7² and 7³ can be used as a single set in coöperation with the set of setting disks 69², for which purpose the carriage 1 is if necessary shifted to the right and in the direction of the arrow 1' until the set of numeral wheels 7³ is in position for coöperation with the setting mechanism 69².

The number of the numeral wheels of the revolutions counting mechanism 78 must be such, that the single tooth which is located in the plane indicated by the arrow x in Fig. 1 is still in coöperation with the revolutions counting mechanism 78, if the carriage 1 has been shifted to the right into position with the numeral wheels 7³ in coöperation with the setting mechanism 69².

The apparatus can also be used without shifting the carriage to the right to such an extent as described, because between the numeral wheels 7² and 7³ carrying means have been provided, so that large numbers can be displayed by the combined numeral wheels 7² and 7³.

If desired a larger number of setting mechanisms can be provided each of which coöperates with its own registering mechanism, all the registering mechanisms being located one beside the other in uninterrupted succession.

I claim herein as my invention:

1. In a calculating machine, the combination of a plurality of setting mechanisms, a plurality of registering mechanisms, one for each of said setting mechanisms, the registering mechanisms being coaxially arranged, and carrying means common to the registering mechanisms and shiftable longitudinally to bring one of said registering mechanisms into operative association with either one of said setting mechanisms without operating the remaining registering mechanism.

2. In a calculating machine, the combination of a plurality of setting mechanisms, a plurality of registering mechanisms one for each of said setting mechanisms and revolutions counting mechanism, the registering mechanisms being arranged coaxially with relation to each other, and carrying means provided between successive registering mechanisms.

3. In a calculating machine, the combination with a plurality of setting mechanisms,

and a plurality of registering mechanisms one for each of said setting mechanisms, of means to bring one of said setting mechanisms into coöperation with either one of 5 said registering mechanisms, and carrying means provided between successive registering mechanisms.

4. In a calculating machine, the combination with a plurality of setting mechanisms, of a plurality of registering mechanisms one for each of said setting mechanisms and arranged coaxially of each other on a longitudinally shiftable common carriage adapted to be moved into position relatively to either one of said registering mechanisms in coöperation with one of said setting mechanisms, and revolutions counting mechanism having its counting members on said carriage.

20 5. In a calculating machine, the combination with a plurality of setting mechanisms located one beside the other and each comprising a plurality of setting disks having teeth arranged about their circumferences and means coöoperating with each of said setting disks to throw the desired number of teeth into operative position, and a plurality of registering mechanisms one for each of said setting mechanisms, of means 25 to bring one of said setting mechanisms into coöperation with either one of said registering mechanisms.

6. In a calculating machine, the combination with a plurality of setting mechanisms located one beside the other and each comprising a plurality of setting disks having teeth arranged about their circumferences and means coöoperating with each of said setting disks to throw the desired number of 35 teeth into operative position, of a plurality of registering mechanisms one for each of said setting mechanisms and arranged coaxially of each other on a common carriage adapted to be shifted into position with either one of said registering mechanisms in coöperation with one of said setting mechanisms.

40 7. In a calculating machine, the combina-

tion with a plurality of setting mechanisms, of a plurality of registering mechanisms one 50 for each of said setting mechanisms and arranged coaxially of each other on a common carriage adapted to be shifted into position with either one of said registering mechanisms in coöperation with one of 55 said setting mechanisms, and carrying means provided between successive registering mechanisms.

8. In a calculating machine, the combination with a plurality of setting mechanisms, and a plurality of registering mechanisms one for each of said setting mechanisms, of means to bring one of said setting mechanisms into coöperation with either one of said registering mechanisms, and 60 revolutions counting mechanism taking part in the relative displacement of said setting and registering mechanisms and arranged to be in operative position in any position of said setting and registering mechanisms 65 relatively to each other.

9. In a calculating machine, the combination with a plurality of setting mechanisms, of a plurality of registering mechanisms one for each of said setting mechanisms and arranged coaxially of each other on a common carriage adapted to be shifted into position with either one of said registering mechanisms in coöperation with one of 75 said setting mechanisms, and revolutions counting mechanism arranged with its counting members on said carriage and with the operating member for the counting members moving with said setting mechanisms, the number of said counting members being 80 such, that the operating member is in any operative position of said registering mechanisms in operative position relatively to the counting members.

In testimony whereof I have hereunto set 90 my hand in presence of two subscribing witnesses.
